UNITED STATES PATENT OFFICE.

CHARLES D. SMITH, OF WASHINGTON, DISTRICT OF COLUMBIA.

IMPROVEMENT IN BUTTON-HOLES.

Specification forming part of Letters Patent No. 57,202, dated August 14, 1866.

To all whom it may concern:

Be it known that I, CHARLES D. SMITH, of the city and county of Washington, in the District of Columbia, have invented a new and useful Improvement in Button-Holes for Shirt-Collars and other Articles; and I do hereby declare the following to be a full, clear, and exact description of the same, reference being had to the accompanying drawing, which is made part of this specification, and represents a perspective view of a collar with my invention applied.

This invention consists in strengthening a button-hole by binding the same with metal, which is clamped in after the manner of an eyelet, so as to extend continuously around and protect the button-hole.

The following description, in connection with the accompanying drawing, will enable one to fully understand and use the invention, which I have shown as applied to a collar.

A represents a collar, which may be of any form or style, and b represents the button-holes. The button-holes are made round to receive an eyelet, a. The eyelet is fixed or clamped in the collar in any suitable way, and by its shape, or the shape of the button, it is adapted to be passed over the latter and be detained so as to attach the collar to the neck-band of the shirt.

The invention may be most useful in its application to paper collars; but its usefulness is supposed to extend to collars made of linen and other material.

The drawing represents the eyeleted button-holes only at the extremities of the collar, the intermediate button-hole—that which fastens at the back of the neck—being sufficiently

strong without the eyelet to outlast the collar. The eyelet may, however, be applied at this point, if preferred.

A button of soft rubber or other suitable flexible or elastic material may be found best suited for the eyelet.

The eyelets may be of elliptical or any other desired shape, the object and extent of the invention being the application of a metallic binding to the button-hole.

The invention is applicable to all garments or articles of wearing-apparel, such as coats, pantaloons, vests, and suspenders; also to carriage-curtains and other articles where button-holes are used.

This invention is restricted to the binding of such button-holes as are to be used in connection with an elastic or other button, and it does not have reference to the apertures through which lacings or cords are passed.

I am aware that hooks and eyes and apertures essentially of metal have been previously used as an attaching or fastening medium.

My invention depends exclusively on the application of the metallic binding to button-holes in flexible material, and is especially intended for such as are made in soft or yielding leather and in fibrous and textile fabrics.

Having thus described my invention, the following is what I claim as new and desire to secure by Letters Patent:

A button-hole having a continuous metallic binding, substantially as and for the purpose specified.

CHARLES D. SMITH.
